United States Patent Office

Des. 209,292
Patented Nov. 21, 1967

209,292

BAR CART

Nicholas A. Ungaro, Louisville, Ky., assignor to Kroehler
Mfg. Co., Naperville, Ill., a corporation of Illinois

Filed Nov. 3, 1966, Ser. No. 4,530

Term of patent 14 years

(Cl. D33—19)

FIG. 2.

FIG. 1 is a front perspective view of a bar cart showing my new design;

FIG. 2 is a similar view showing my new design in open position.

The end not shown is a mirror image of the end shown, and the back is plain.

The essential features of the design reside in the parts shown in full lines.

I claim:

The ornamental design for a bar cart, as shown and described.
